UNITED STATES PATENT OFFICE.

ROBERT S. ASPINWALL, OF CLEVELAND, OHIO, ASSIGNOR TO THE VIRDEN MANUFACTURING COMPANY, A CORPORATION OF OHIO.

DESIGN FOR A SHELL FOR LIGHTING-FIXTURES OR SIMILAR ARTICLES.

44,700.

Specification for Design.

Patented Sept. 30, 1913.

Application filed August 9, 1913. Serial No. 783,960. Term of patent 7 years.

To all whom it may concern:

Be it known that I, ROBERT S. ASPINWALL, a citizen of the United States, residing at Cleveland, county of Cuyahoga, and State of Ohio, have invented a new, original, and ornamental Design for Shells for Lighting-Fixtures or Similar Articles, of which the following is a specification, reference being had to the accompanying drawing, forming part thereof.

The drawing is a perspective view of a shell, showing my new design.

I claim:

The ornamental design for a shell for lighting fixtures or similar articles, as shown.

ROBERT S. ASPINWALL.

Witnesses:

KARL FENNING,
FLORINE EVANS.
